1, adjustable table and floor lamps, Dec. 1990.

Primary Examiner—Susan J. Lucas

[57] **CLAIM**

The ornamental design for an adjustable lamp, as shown and
described.

DESCRIPTION

FIG. 1 is a front, left side perspective view;

FIG. 2 is a front elevational view;

FIG. 3 is a rear elevational view;

FIG. 4 is a front, left side perspective view of a second
embodiment of the adjustable lamp of my design;

FIG. 5 is a left side elevational view of the first embodiment
of the claimed design;

FIG. 6 is a top plan view on an enlarged scale; and,

FIG. 7 is a bottom plan view on an enlarged scale.

The first embodiment differs from the second embodiment
only by its elongated, vertical standard.
